NELSON B. WHITAKER, OF PROVIDENCE, RHODE ISLAND.

ANCHORING MEANS FOR ARTIFICIAL TEETH.

1,279,805.

Specification of Letters Patent. Patented Sept. 24, 1918.

Application filed September 27, 1917. Serial No. 193,564.

To all whom it may concern:

Be it known that I, NELSON B. WHITAKER, a citizen of the United States, residing at Providence, in the county of Providence,

5 State of Rhode Island, have invented certain new and useful Improvements in Anchoring Means for Artificial Teeth, of which the following is a specification.

My invention relates to artificial teeth and 10 consists of an improved means for anchoring or fastening the individual teeth to the plate or backing on which they are mounted in forming "sets" or dentures.

The object of my improvement is to provide a tooth having a more natural form 15 and appearance and adapted to be fastened to the plate with greater security, while at the same time allowing for its removal and replacement should occasion require. Further objects of the invention are to render the tooth applicable to either metal, vulcanite or composition plates, and to provide for setting it without heat so as to avoid discoloration of the porcelain.

20 The manner and means for carrying out the improvement are fully disclosed in the following specification, illustrated by the accompanying drawings, in which like reference characters designate like parts. In the drawings:—

Figure 1 is a sectional view of my improved denture shown in magnified size and illustrating the method of attaching or anchoring the tooth to the plate;

Fig. 2, a detail view of that part of the anchoring-means for the tooth which is fastened to the plate;

Fig. 3, a detail view of the anchoring-element which is embedded in the tooth, 40 showing a slightly modified form thereof;

Fig. 4, a side view of the same;

Fig. 5, a detail view of the anchoring-stud or screw; and

Fig. 6, a view showing a method of securing the anchoring-means to a metal plate.

Referring first to Fig. 1, T designates an artificial tooth which may be molded from porcelain or other similar material in the usual manner, it being noted that the base 50 of the tooth is relatively broad and concaved while its sides taper upwardly to the cutting edge at the top. In this form my improved tooth simulates the natural configuration of human incisors which are of

55 more or less wedge-shape as shown. Inserted in the body of the tooth near its base,

where it is of greater diameter, is a vertical tube B, preferably constructed from nickel or some other non-corrosive metal and usually baked into the enamel after the latter has been molded around it. As shown particularly in Figs. 3 and 4 the tube B is flattened and closed at one end and has projections or lobes b, b on its sides. In Fig. 1 the lobe or lug b of the tube B projects from one side only, but in Figs. 3 and 4 the method of forming the end of the tube provides two projections or lugs b, b on opposite sides, making a sort of spear-head with a sharp point b' at its end. The flattening of the tube B at its end is designed to prevent it from turning within the tooth T and the side lobes b provide abutments to anchor the tube in place and prevent its withdrawal. Below the tube B the tooth is formed with a cylindrical opening adapted to receive the end of another tube C which is secured to the plate P, see Fig. 1. The tube C is flanged out at its bottom, see Fig. 2, to provide a cylindrical head or mushroom base for anchoring it in the vulcanite plate P.

In applying the tube C to a metal plate the flaring base c is soldered directly thereto as shown in Fig. 6. After the tube C has been secured in place on the plate P the tooth T is slipped onto its end which projects from the top of the plate and a screw S is then inserted therethrough from the bottom. The screw S, as shown in detail in Fig. 5, has a chamfered head s which fits the flaring opening at the lower end of the tube C and its end is threaded to screw into the threaded bore of the tube B. The tube C locates the tooth T in position on the plate P and the screw S is inserted from the under side and screwed up into the tube B to draw the tooth down onto the plate with its concaved base fitting snugly thereagainst. An opening o is left in the under side of the plate P through which to insert the screw S and after the tooth has been attached this may be filled with cement p to make a smooth finish. When it is required to detach a tooth from the plate for repair or replacement, it is only necessary to heat the cement p to remove it in order to allow access to the head of the screw S so that the latter may be unscrewed and the tooth taken off of the anchoring-tube C.

Referring to Fig. 6, in securing the tooth on a metal plate M the tube C is soldered

thereto, and a filister-headed screw S' is then inserted from the under side of the plate to draw the tooth into place. The plate M is usually covered with vulcanite molded there-around, and this may be applied after the tube C has been fastened in position. In either case the tube C serves to locate the tooth on the plate, and the screw S secures it fixedly in position.

10 The tube C may be made of different lengths to adapt it for different styles of plates and different lengths of teeth, and if preferred the ends of the two tubes B and C may be made to abut within the bore of 15 the tooth T.

In forming the artificial denture the tube C is first attached to the plate by molding it into the vulcanite, or in the case of platinum, gold or silver plates by soldering or riveting 20 its flange c to the metal thereof. In positioning the anchoring-tubes C on the plate P the teeth T are applied to their ends in order to locate them properly, but the teeth are removed when the tubes C are fastened to the 25 plate. In some cases in soldering the tube C to the plate M, or in molding it into the vulcanite P, the screw S is inserted through it to prevent its bore from being filled with the material; or, if preferred, the bore may be 30 filled with plaster of Paris or some other material which can be easily removed. After the tubes C are attached to the plate the teeth T are applied thereto as above described, and the screws S inserted to draw them down 35 into place. In this way the teeth T are not subjected to heat during the process of fastening their anchoring-means to the plate P, or M, as the case may be, so that the porcelain will not be injured or discolored. After the 40 screws S have been inserted the openings in the bottom of the plate are filled with a cement which may be softened by heating to provide access to the screws when necessary as above explained. When the denture is 45 completed the teeth are secured fixedly and rigidly in place on the plate, and their anchoring-means are entirely concealed so that a smooth and finished appearance is given to the whole structure.

The anchoring-tubes B which are molded 50 in the tooth T are of relatively small diameter, and their flattened ends, while serving to hold them from turning in the teeth and from withdrawal therefrom, at the same time do not weaken the structure of the 55 molded porcelain. That is to say, the anchoring-means occupies a relatively small space within the lower body of the tooth where its breadth is greatest so that the structure of the tooth is not weakened. The 60 tube C which enters the base of the tooth serves to locate it in position in fitting the teeth to the plate, but, as before stated, the teeth may be removed from their anchoring-means when the latter are fastened to the 65 plate so that they will not be damaged or discolored by the heat. My improvement provides for manufacturing the teeth in various forms and shades in accordance with 70 nature's models with their fastening-means fitted thereto to be furnished as a complete article of commerce for the purpose intended. In some cases the anchoring-tubes C are made of a considerable length in accordance 75 with the requirements for dentures in which the teeth are set well away from the plate. For closer settings these tubes may be filed or ground down, and therefore the whole device is interchangeable for dentures of 80 different styles and forms, lengths and sizes. 80

Various modifications might be made in the form and structure of the parts of the anchoring-means without departing from the spirit or scope of the invention; therefore, without limiting myself to the exact 85 details of construction shown and described, what I claim is:—

In an artificial denture, the combination with an anchoring-tube having an extended base adapted to be attached to the plate, of 90 a molded tooth having a vertical tube baked into its body, and a screw inserted through the bore of the anchoring-tube and screwed into the threaded bore of the tube in the tooth to draw the latter into place against 95 the plate.

In testimony whereof I affix my signature.
NELSON B. WHITAKER.
